UNITED STATES PATENT OFFICE

2,589,480

AUTOMATIC DOOR OPERATOR

Guy A. Curtis, Cleveland Heights, Ohio, assignor to United States Motors Corporation, Oshkosh, Wis., a corporation of Wisconsin

Application April 5, 1951, Serial No. 219,454

6 Claims. (Cl. 268—59)

1

This invention relates to improvements in automatic door operators, and more particularly to a motor driven operator for a garage door, preferably, although not necessarily of the sectional "overhead" type.

In my prior application Serial No. 46,956, filed August 31, 1948, I have disclosed a power driven door operator wherein an endless chain, having elements of the door operating mechanism connected to the opposite runs thereof, is driven by a unidirectional electric motor with the provision of control means for automatically breaking the motor circuit as the door completes its movement in either the opening or closing operation. The door operator of my prior application above identified is furthermore of such nature that the power driven means will not interfere with manual operation of the door.

While, generally speaking, the present automatic door operator embodies the above desirable features of my prior application, it incorporates certain improvements and refinements thereover. The present improved structure utilizes between the motor and endless chain, a worm drive and the endless chain is housed in a simplified tube of circular form in cross section.

Further specific objects of the invention are to provide in an automatic door operator of the character described an improved double trolley arrangement which will permit adjustments in the door operating mechanism to compensate for doors of varying heights, together with an improved link arrangement between the door and the door operating mechanism.

A further more specific object of the invention is to provide in an automatic door operator of the character described, improved means for permitting adjustments to obtain various lengths of door travel within certain limits.

A further object of the invention is to provide, in an automatic door operator, means controlled by the movement of the door for automatically locking the latter in closed position, which means may also be key controlled and manually operated.

A further more specific object of the invention is to provide in an automatic door operator of the character described, means whereby the drive for the door becomes disengaged upon manual movement of the door whereby the door may be easily, manually operated without the drag of the associated power mechanism.

A further object of the invention is to provide an automatic door operator which is of very simple construction, is strong and durable, is

2

easy to install, is efficient in operation, which is relatively inexpensive, and which is well adapted for the purposes set forth.

With the above and other objects in view the invention consists of the improved automatic door operator and its parts and combinations as set forth in the claims, and all equivalents thereof.

In the accompanying drawings in which the same reference characters indicate the same parts in all of the views:

Fig. 1 is a vertical sectional view of a garage door provided with the improved automatic door operating mechanism with the door being shown in full lines in its fully closed position and in broken lines in its overhead open position;

Fig. 2 is an enlarged fragmentary sectional view of the upper portion of a building equipped with an overhead door, a fragment of the latter being shown in section, illustrating in side elevation the improved door operating mechanism with portions of the latter being broken away and in section to show structural details;

Fig. 3 is an enlarged plan view of the housing tube, chain, carriage and motor drive portion of the mechanism shown in Fig. 2 with portions broken away and in section to show structural details;

Fig. 4 is a cross sectional view taken on line 30 4—4 of Fig. 2, and on a larger scale; and

Fig. 5 is an enlarged fragmentary sectional view of the rear end of the housing tube with the carriage and chain in door raised position, showing also the electric motor and a diagram of the 35 motor and control circuits.

With particular reference to Fig. 1 of the drawings it will be observed that the garage door illustrated is of the "overhead" type and is formed of a plurality of sections 10 hinged together horizontally and provided along their side edges with laterally projecting shoes 11 running in tracks at the opposite sides of the door frame, with each track including a straight vertical section 12, an overhead horizontal section 13 and an interconnecting curved section 14.

Designed to occupy an overhead position immediately below the ceiling or roof 15 of the garage or building and above the horizontal sections 13 of the tracks, preferably intermediate said tracks, is a guide or chain housing 16 in the form of a hollow metallic tube of circular form in cross section (see Fig. 4) and extending rearwardly from the door opening. Along the bottom side of said tubular guide or housing 16 is an elongated slot 17. Adjacent the opposite

ends of the tubular guide housing 16 are journaled shafts 18 and 19. Upon the shaft 19 within the tubular housing 16 is a relatively small sprocket 20, with a similar sprocket 21 being secured fast on an intermediate portion of the shaft 18, which is elongated and which is a driven shaft. An endless chain 22, within the housing member 16, is trained about said sprockets 20 and 21.

Carriages 23 and 23' are mounted to slide back and forth within the tubular guide housing 16. The body portions of said carriages are cylindrical and each has a depending fin 24 and 25 projecting through the housing slot 17 and adjustably secured by bolts 26 to a bi-layered metal strap 27 in which is provided a series of apertures 28 for the selective spaced attachment of the carriages 23 and 23'. The series of apertures 28 in the strap 27 permit relative spacing of the carriages 23 and 23' for adjustment purposes. At the forward end of the strap 27 there is a right angularly disposed depending extension 27', of bi-layered formation and between the layers thereof is pivotally secured the upper end of a link 31. As will be observed from Fig. 2, the upper portion of said link 31 which is embraced between the layers of the strap portion 27', is provided with a series of apertures 29 and for adjustment purposes the pivotal connection 30 may be inserted through a selected aperture 29.

The link 31 is formed with a hollow cylindrical portion 32 housing a coiled spring 33 to which is connected the inner end of a bell crank lever 34 pivotally mounted on a plate 35 rigidly secured to and projecting inwardly from the uppermost door section 10. Said plate 35 has a horizontal series of spaced apertures 36, any one of which may be selected for the pivot pin 37 of the bell crank lever 34, for adjustment purposes. The lower free end of the bell crank lever 34 carries one end of a chain 38 which, as will hereafter appear, has its lower end connected to the door locking and latching hardware. At this point it may be stated that as the carriage 23 moves from the position of Fig. 2 to the position of Fig. 5, the sectional door slides to a raised overhead position along its guide track sections 12, 14 and 13. As will hereinafter appear, the chain drive is so arranged that the carriage 23 is pushed toward the right relative to the drawings from the broken line position, these being the two extreme positions of the door and door operating mechanism.

The sprocket wheel 20 for the chain drive is an idler while the sprocket wheel 21 is driven by a worm 39 which meshes with a worm wheel 40 which normally drives the shaft 18 through a clutch arrangement 41 which will break the drive should there be an overload or a jamming of any of the driven parts. The worm 39 is driven by the motor shaft 42 of an electric motor 43, the motor being a non-reversible or uni-directional motor.

The carriage member 23 is provided with a pair of horizontal projections 44 spaced apart sufficiently to permit the lower run of the chain 22 to pass therebetween. The upper portion of the carriage 23 has two similar projections 45 between which the upper run of the chain may pass. Secured transversely to the chain 22 is a switch operating lug 46 which is sufficiently short to permit its passage between the spaced projections 44 or 45. Rearwardly of the lug 46, considering the direction of travel of the chain 22, is a carriage pushing lug 47 which is somewhat longer than the space between a pair of projections 44 or 45. When the lug 47 is travelling

in the lower run of the chain 22 it engages the projections 44 of the carriage 23 and causes the same to travel toward the left, relative to Figs. 1, 2 and 5, until the extreme position of the carriage 23 is reached, shown in Fig. 5, whereupon the arc of travel of the chain around the sprocket 21 causes the lug 47 to move free of the projections 44 and ultimately reach the upper flight of travel of the chain 22. Upon further movement of the chain the carriage pushing lug 47 will then engage the projections 45 of the carriage 23', causing the same to travel toward the right relative to Figs. 1, 2 and 5, until the extreme position of said carriage is reached, shown in full lines of Fig. 1, at which time the door will be in its vertical closed position and the lug 47 will ride around the sprocket 20 free of the carriage projections 45. It is obvious that the carriages 23 and 23' are adjusted relative to the strap 27 and the members 31 and 34 are so adjusted relative to their mountings so that when the lug 47 leaves the projections on the carriages, the door is either in its fully open or in its fully closed position.

An electric microswitch is indicated by the numeral 48. Operatively mounted on the lower surface of the casing of the switch 48 is a switch-operating arm 49 controlling a switch plunger 50 which is biased downwardly and toward switch closing position. As will be observed from Fig. 5, the spacing relation of the lugs 46 and 47 on the chain 22 is such that when the lug 47 has pushed the carriage 23 to the fully open position of the door, the lug 46 will be in momentary engagement with the switch-operating arm 49 to lift the switch plunger 50 and thereby open the switch which results in a cessation of operation of the electric motor 43 and the door-operating mechanism, by means of certain electrical connections shown schematically in Fig. 5 and which will now be described. However, the lug 46 always coasts beyond the arm 49 which will permit the lug 47 to clear the projections 44 or 45.

High voltage supply lines 51 include in their circuit a step-down transformer 52. The secondary coil of said transformer is connected to one wire 53 of a low voltage circuit, and another wire 53' in said circuit, and extending from the secondary coil of the transformer, runs to an electro-magnet 54, the other wire 55 of the low voltage line being connected to the other terminal of the electro-magnet 54. Wires 53 and 55 may include a switch 56 which is biased toward open position. From a practical standpoint the switch 56 may be a manually operated push button switch or any other type of switch which is open when not positively manipulated to a closed position. When the electro-magnet 54 is engaged by the closing of the switch 56 and armature 57 is electrically engaged with a contact 58 whereby one of the wires 51 is electrically connected with a wire 59 which extends to the electric motor 43. The other wire 60, connected to the electric motor, extends to the other wire 51 of the high voltage line.

When the motor circuit is completed it should be maintained in this condition through one cycle of door operation. For this purpose a holding circuit is bridged across the terminals of the secondary coil of the transformer 52 and includes the previously mentioned wire 53' extending to the electro-magnet, a short extent of the wire 55, a wire 62 leading from wire 55 to an armature contact 63, an armature 64 held in operative relation with the contact 63 by the electro-magnet 54 when the same is energized, a wire 65 leading to

the micro-switch 48, and a return wire 65 from the micro-switch 48 to the opposite side of the secondary coil of the transformer.

The door lock and latch hardware, best shown in Fig. 2, may be more or less conventional and includes a shaft 67 revolvably mounted through a panel of the door and carrying fast on its opposite ends inside and outside handles 68 and 69 with the latter being key-controlled (not shown), if desired. Adjacent the inner face of the door panel 10 and fast on the shaft 67 is an arm 10 to which the lower end of the chain 38 is attached, and the shaft also carries a disc 71 which, when turned, may operate a latch bolt 72 to disengage the latter from said disc 71, allowing the handle 69 to turn the shaft 67.

The link 31 and upper end portion of the bell crank lever 34 are resiliently connected through the medium of the cylinder 32 and housed spring 33. When the door is in its closed vertical position, the link 31 and upper arm of the bell crank lever 34 will be inclined beyond vertical and this arrangement serves to automatically lock the door in closed position. Upon manipulation of the handle 69 or the handle 68 to exert a pull on the chain 38, the bell crank lever 34 is rocked in a counterclockwise direction to thereby throw the connection 31-34 to the other side of the vertical center line, thereby freeing the mechanism to permit movement of the door. If the door is lifted manually through the connection 31-34 and the strap 27, the carriages 23 and 23' move toward the left (relative to the drawings) within the guide housing 16 and manual movement is easily accomplished because said carriages move without movement of the chain 22. Manual closing of the door is a reverse procedure and when the door is closed, either manually or automatically, through the over vertical disposition of the connection 31-34, automatic locking is accomplished.

With respect to automatic or power operation of the overhead door let it first be assumed that the carriage 23 is in the position shown in Fig. 5 or in the broken line position of Fig. 1 wherein the door is fully open. If the operator wishes to set the mechanism into condition for automatically closing the overhead door, he may close the switch 56 momentarily by a manual actuation or through the action of an electrical impulse set in motion by any desired means, as by a remote transmitter. This will cause energization of the electromagnet 54 causing the armatures 57 and 64 to engage the contacts 58 and 63 respectively, whereby the circuit to the motor 43 is completed and the sprocket wheel 21 is driven in a clockwise direction (relative to the drawings). The closing of contacts 58 and 63 also closes the holding circuit. As the chain 22 travels in the direction indicated by the arrows, the lug 46 will advance along the upper flight of the chain 22 and the carriage pushing lug 47 will likewise advance until it contacts the projections 45 on the carriage 23' whereby the carriage will be pushed toward the right, relative to the drawings, and this movement of the carriage, through the strap 27, connections 31-34, and the bracket 35 will push the door from its fully open toward its closed position with such movement continuing until the carriage 23' reaches the position of Fig. 2 whereupon the door will become locked in its closed position, as previously described. Movement of the chain 22 will then continue until the switch operating lug 46 reaches and engages the operating arm 49 for the micro-switch 48, thereby opening the control circuit, deenergizing the electromagnet 54 and

breaking the motor circuit at the points 57 and 58. Then, the chain mechanism comes to a stop. For the opening of the door automatically the same procedure is followed which necessitates the 5 momentary closing of the switch 56 whereupon the switch operating lug 46 will be moved clear of the micro-switch arm 49 and the holding circuit will be established. Thereafter, the carriage pushing lug 47 will engage the projections 44 on the carriage 23 and the carriages will be moved to the left relative to the drawings, causing the connection 31-34 to first move beyond vertical and subsequently elevate the door, with the movement of the carriages continuing until the position of Fig. 5 is obtained whereupon the lug 46 will actuate the micro-switch to open the motor circuit.

In the improved automatic door operator the drive from the electric motor 43 to the driven 20 sprocket 21 which operates the chain 22 is through a worm and wormwheel which is smooth and positive in its action. The clutch mechanism 41 in the driven shaft 18 prevents a possibility of any damage to the drive should 25 there be an overload or obstructions. Through the arrangement shown at the right hand end of Figs. 2 and 3, by turning the bolt 73 the idler sprocket 20 may be shifted slightly fore or aft to vary the tension in the chain 22. The door 30 operator comprises a minimum number of unitary parts which may easily be mounted within a garage and adjustably connected with an overhead door. The various adjustable arrangements simplify the mounting to insure full opening and 35 closing movements of the door. The cylindrical guide housing 16 compactly encloses the major portions of the carriages 23 and 23' and the same may slide within said housing with a minimum friction. The manner in which the operating 40 connections 31-34 move beyond vertical is effective for automatically locking the door and said connections also eliminate shock or strain due to the resilient or snubbing action of the spring 33 which in fact is a connector between the members 31 and 34.

The improved automatic door operator is relatively inexpensive to manufacture and install, is strong and durable and automatic in its operation, is compact and does not interfere with 45 the open overhead position of the door, and is well adapted for the purposes set forth.

What is claimed as the invention is:

1. In a door operating mechanism, a track having a straight section, a guide disposed parallel to said straight section, first and second carriages slidable within said guide, a strap adjustably connecting said carriages in longitudinally spaced relation, a lever adjustably pivotally connected to said strap and adjustably pivotally connected to a door slidable on said track, a sprocket wheel mounted adjacent each end of said guide, an electric motor for turning one of said sprocket wheels in a given direction only, an endless chain running over said sprocket wheels, a protuberance 55 mounted on said chain adapted when travelling along one flight thereof to engage said first carriage and push it in one direction and adapted when travelling along the other flight of the chain to engage said second carriage and to push it in the other direction the movement of the protuberance around either sprocket wheel disengaging it from a carriage and permitting movement of the connected carriages independently of said chain, a circuit for said electric motor, 60 a switch in the motor circuit, and a second

7 protuberance carried by said chain in spaced relation to the first mentioned protuberance for operating said switch to automatically terminate travel of the chain when either carriage is at the end of its path of movement within said guide.

2. In a door operating mechanism, a track having a straight section, a tubular, cylindrical guide disposed parallel to said straight section, first and second carriages slideable within said guide, 10 a strap adjustably connecting said carriages in longitudinally spaced relation, a lever adjustably pivotally connected to said strap and adjustably pivotally connected to a door slideable on said track, a sprocket wheel mounted adjacent each end of said guide, an electric motor, a worm and worm wheel drive between said motor and one of said sprocket wheels for turning the latter in a given direction only, a clutch associated with said drive, an endless chain running over said sprocket wheels, and a protuberance mounted on said chain adapted when travelling along one flight thereof to engage said first carriage and push it in one direction and adapted when travelling along the other flight of the chain to engage said second carriage and to push it in the other direction, the movement of the protuberance around either sprocket wheel disengaging it from a carriage and permitting movement of the connected carriages independently of said chain.

3. In a door operating mechanism, a track, a horizontally disposed guide, first and second carriages slideable within said guide, a horizontally disposed strap adjustably connecting said carriages in longitudinally spaced relation, a lever adjustably pivotally connected to said strap and adjustably pivotally connected to a door slideable on said track and having its major extent substantially vertically disposed, there being a resilient section in said lever, a sprocket wheel mounted adjacent each end of said guide, an electric motor for turning one of said sprocket wheels in a given direction only, an endless chain running over said sprocket wheels, a protuberance mounted on said chain adapted when travelling along one flight thereof to engage said first carriage and push it in one direction and adapted when travelling along the other flight of the chain to engage said second carriage and to push it in the other direction, the movement of the protuberance around either sprocket wheel disengaging it from a carriage and permitting movement of the connected carriages independently of said chain, the movement of said first carriage in one direction opening the door to which said lever is connected and the movement of said second carriage in the opposite direction closing the door to which the lever is connected, said lever in pushing the door to its closed position, inclining to one side of vertical to thereby releasably lock the door in its closed position.

4. In a door operating mechanism, a track having an overhead horizontal straight section, a guide disposed above and parallel to said straight section, first and second carriages slideable within said guide, a horizontal strap adjustably connecting said carriages in longitudinally spaced relation, a generally vertically disposed bell-crank lever adjustably pivotally connected to said strap and adjustably pivotally connected to a door slideable on said track, a sprocket wheel mounted adjacent each end of said guide, an electric motor for turning one of said sprocket wheels in a given direction only, an endless chain running over said sprocket wheels, a protuberance

5 mounted on said chain adapted when travelling along one flight thereof to engage said first carriage and push it in one direction and adapted when travelling along the other flight of the chain to engage said second carriage and to push it in the other direction, the movement of the protuberance around either sprocket wheel disengaging it from a carriage and permitting movement of the connected carriages independently of said chain, a circuit for said electric motor, a switch in the motor circuit, and a second protuberance carried by said chain in advance of the first mentioned protuberance for operating said switch to automatically terminate travel of the chain when either carriage is at the end of its path of movement within said guide.

20 5. In a door operating mechanism, a track having a straight section, a tubular, cylindrical guide disposed parallel to said straight section, first and second carriages having cylindrical portions slideable within said guide, a strap exteriorly of said guide adjustably connecting said carriages in longitudinally spaced relation, a lever adjustably pivotally connected to said strap and adjustably pivotally connected to a door slideable on said track, a connection for manually rocking said lever, a sprocket wheel mounted adjacent each end of said guide, an electric motor, a worm and worm wheel drive between said motor and one of 30 said sprocket wheels for turning the latter in a given direction only, a clutch associated with said drive, an endless chain running over said sprocket wheels, means for adjusting the tension of said chain, and a protuberance mounted on 35 said chain adapted when travelling along one flight thereof to engage said first carriage and push it in one direction and adapted when travelling along the other flight of the chain to engage said second carriage and to push it in the other direction, the movement of the protuberance around either sprocket wheel disengaging it from a carriage and permitting movement of the connected carriages independently of said chain.

40 6. In a door operating mechanism, a track, a horizontally disposed guide, first and second carriages slideable within said guide, a horizontally disposed strap adjustably connecting said carriages in longitudinally spaced relation, a bell-crank lever adjustably pivotally connected at one end portion to said strap and adjustably pivotally connected to a door slideable on said track and having its major extent substantially vertically disposed, there being a resilient section in said lever, a sprocket wheel mounted adjacent each end of said guide, an electric motor, a worm and worm wheel drive between said motor and one of said sprocket wheels for turning the latter in a given direction only, a clutch associated with said drive, an endless chain running over said sprocket wheels, a protuberance mounted on said chain adapted when travelling along one flight thereof to engage said first carriage and push it in one direction and adapted when travelling along the other flight of the chain to engage said second carriage and to push it in the other direction, the movement of the protuberance around either sprocket wheel disengaging it from a carriage and permitting movement of the connected carriages independently of said chain, the movement of said first carriage in one direction opening the door to which said lever is connected and the movement of said second carriage in the opposite direction closing the door to which the lever is connected, said lever in pushing the door

to its closed position, inclining its major extent to one side of vertical to thereby releasably lock the door in its closed position, and a connection extending to said bell-crank lever for manually rocking the major extent to the other side of vertical for door unlocking purposes.
